Patented Feb. 3, 1959

184,334

DRINK STIRRER

Victor J. Bergeron, Orinda, Calif.

Application July 9, 1958, Serial No. 51,710

Term of patent 14 years

(Cl. D44—1)

Fig. 1

Fig. 2

Figure 1 is a front elevational view of a drink stirrer showing my new design; and

Figure 2 is an edge elevational view thereof.

The rear face of the drink stirrer shown in Figure 1 is plain and unornamented.

I claim:

The ornamental design for a drink stirrer, as shown and described.
